COMBINED BRUSH AND SHOE HORN

Eric Seger, London, England, assignor to Frederick Wicks
and Company Limited, London, England, a British
company

Filed Sept. 5, 1967, Ser. No. 8,502

Term of patent 7 years

Claims priority, application Great Britain Mar. 17, 1967

(Cl. D4—17)

FIGURE 1 is a front view of the combined brush and shoe horn showing my new design;

FIG. 2 is a side view of the combined brush and shoe horn taken from the right of FIG. 1;

FIG. 3 is a side view thereof taken from the left of FIG. 1;

FIG. 4 is a rear view of the combined brush and shoe horn;

FIG. 5 is a top plan view of the combined brush and shoe horn, and

FIG. 6 is a bottom plan view of the combined brush and shoe horn.

I claim:

The ornamental design for a combined brush and shoe horn, substantially as shown.
